UNITED STATES PATENT OFFICE.

RICHARD E. KIDDER, OF WORCESTER, MASSACHUSETTS; WORCESTER TRUST COMPANY
EXECUTOR OF SAID KIDDER, DECEASED.

MULTIPLE-SPINDLE BORING-MACHINE.

1,151,018.

Specification of Letters Patent. Patented Aug. 24, 1915.

Application filed September 6, 1912. Serial No. 718,861.

To all whom it may concern:

Be it known that I, RICHARD E. KIDDER, a citizen of the United States, residing at Worcester, in the county of Worcester and 5 Commonwealth of Massachusetts, have invented a new and useful Improvement in Multiple-Spindle Boring-Machines, of which the following is a specification, accompanied by drawings forming a part of 10 the same.

My invention relates to boring machines and more particularly to a boring machine which comprises a plurality of spindles carrying boring tools for making simultaneously 15 a plurality of holes in a piece of work.

In certain kinds of work, it is sometimes necessary or desirable to bore a plurality of holes, the number of holes and their arrangement often varying in different pieces 20 of work according to different requirements. When the arrangement of such holes has permitted, it has been customary to form a part or all of them simultaneously with a multiple spindle boring machine, with a resultant saving of time and labor.

My invention comprises a machine of the type just referred to, and an object of the invention is to construct such a machine so that it may be adjusted to form the holes 25 in any relative positions desired within certain limits. The adjustment may be such that the holes may be located in a straight or broken line or in a regular or irregular curve. It is, therefore, not necessary to provide 30 separate machines to form holes in different relative positions.

My invention will be described in detail in connection with the accompanying drawings, in which—

40 Figure 1 is a side view of one form of machine embodying my invention; Fig. 2 is a top view of the same machine; and Fig. 3 is a detail vertical sectional view on the line 3 of Fig. 2.

45 Similar reference characters indicate like parts in the different figures.

The base 1 of the machine has firmly secured to its top a table 2 which supports the tools and the driving mechanism therefor.

50 Extending upwardly from the central rear portion of the table 2 is a post 3 carrying a horizontal front arm 4 and a horizontal

rear arm 5 at its top, and the post 3 also carries a second horizontal front arm 6 spaced below the arm 4. These front arms 55 carry bearings 7 and 8 at their forward ends, the two bearings being in vertical alinement to support a vertical rotatable spindle 9, the lower end of which is adapted to carry a boring tool.

60 Two more posts 10 and 11 extend upwardly from the table 2, one on each side of the post 3. These two posts, the parts they carry and the method of mounting them are similar so that one only need be described 65 in detail to make clear the construction of both.

70 The post 10 carries two horizontal front arms 12 and 13 with bearings 14 and 15 at their front ends, these bearings being in vertical alinement to support a second vertical rotatable spindle 16 spaced laterally from the spindle 9 and also adapted to carry a boring tool at its lower end. A third rotatable spindle 17 adapted to carry a boring 75 tool at its lower end is carried in a similar manner by the post 11, as will be readily understood, and is spaced from the spindle 9 on the opposite side thereof from the spindle 16.

80 The arm 5 carried by the post 3 is provided at its rear end with a bearing 18 supporting the upper end of a vertical shaft 19, the lower end of which is supported by a rear extension 20 of the table 2. This 85 shaft 19 carries a series of pulleys 21, corresponding in number to the number of rotatable tool carrying spindles. Each of the spindles has a pulley fixed thereon in suitable position to be driven by a belt from one 90 of the pulleys on the shaft 19.

85 The rear extension 20 of the table 2 supports a driving shaft 22 having a tight and loose pulley 23 on one end, and having its other end connected to the shaft 19 by bevel 95 gears 24. It is obvious that the construction described is such that a series of tools carried by the multiple spindles 17, 9 and 16 may be driven simultaneously by a suitable belt adapted to run on the tight and loose 100 pulley 23.

In order that the relative positions of the spindles and the tools carried thereby may be adjusted so as to bore holes in different rela-

tive positions in a piece of work as already referred to, the posts 10 and 11 are each adjustably mounted on the table 2.

A horizontal guideway 25 is provided in 5 the top of the table 2 and under the post 10 and a slide 26 is carried in this guideway, the edges of the slide and the sides of the guideway being shaped as shown to prevent all movement of the slide except longitudinally of the guideway. The post 10 has an 10 extended base which is mounted on the slide 26, and this post with the parts it carries may be swung in a horizontal plane about the pivot 27 fixed to the slide and eccentric 15 to the axis of the spindle 16 carried by the post. The post 10 is secured to the slide 26 and held in any desired angular adjustment, within reasonable limits, by means of the 20 screw bolts 28, these bolts being carried by the slide 26 and passing through slots 29 which are curved in arcs having the pivot 27 as their center to permit the post to swing when the bolts are loosened.

A hand screw 30 is carried by a flange 31 25 at the rear of the table 2, and this hand screw carries a collar on each side of the flange to prevent longitudinal movement of the hand screw in either direction. This hand screw enters a threaded opening in the 30 rear end of the slide 26 and serves to adjust the slide and the mechanism carried thereby, including the spindle 16, longitudinally of the guideway 25 and to maintain them in adjusted position.

35 The provisions described for the adjustment of the spindle 16 are duplicated in connection with the spindle 17, as has already been indicated.

It is obvious that many adjustments of 40 the spindle 16 would vary the distance between this spindle and the shaft 19, thereby tending to tighten or loosen the belt connecting this shaft and spindle. To keep the different belts under proper tension under 45 these varying conditions, belt tighteners 32 of any suitable construction are provided.

A work support 33 is carried on a slide 34 mounted in the table 2 in proper position under the tool carrying spindles. 50 A piece of work to be bored is laid upon the work support and raised against the boring tools by raising the work support by means of a treadle 35 and suitable connections.

55 It is obvious that an adjustment of the position of the spindle 16 either about the pivot 27 or longitudinally of the guideway 25 will vary its spacing from the spindle 9, and will also vary the shape of the horizontal 60 line through which the spindles pass; and it is also obvious that both adjustments make it possible to locate the three spindles in any desired relative positions within certain limits.

I do not wish my invention to be limited 65 to the specific construction shown and described, as changes may be made within the scope of the appended claims without departing from the spirit thereof, but

Having described the preferred form of 70 my invention, what I claim as new and desire to secure by Letters Patent is:

1. In a multiple boring machine, a horizontal table, a fixed vertical post mounted on said table and provided with horizontal 75 arms, a boring spindle journaled in said arms, a driving shaft journaled in bearings parallel with said boring spindle, means for rotating said driving shaft, a vertical post adjustably supported by said table at one 80 side of said fixed post, and provided with horizontal arms, a boring spindle journaled in said arms, and belt connections between said boring spindles and said driving shaft.

2. In a multiple boring machine, a horizontal table, a fixed vertical post mounted on said table, a vertical boring spindle supported by said post, a driving shaft supported by said post and parallel with said boring spindle, means for rotating said driving shaft, a slide adjustably held in ways on 90 said table, a second vertical post mounted on said slide, a boring spindle supported by said second post and parallel with said driving shaft, and a belt connection between 95 said boring spindles and said driving shaft.

3. In a multiple boring machine, a horizontal table, a vertical post rigidly mounted thereon, a boring spindle supported by said post, a driving shaft parallel with said boring spindle, means for rotating said shaft, a slide adjustably held on said table, a second vertical post mounted on said slide, a boring spindle supported by said second post, belt connections between said boring spindles and said driving shaft, and means for 100 adjusting said second vertical post rotatively on said slide about an axis eccentric to the axis of its boring spindle.

4. In a multiple boring machine, a horizontal table, a vertical post rigidly mounted on said table, a boring spindle supported by said post, a driving shaft parallel with said boring spindle, means for rotating said driving shaft, a second vertical post supported 110 by said table, a boring spindle supported by said second post, means for adjusting said second post in a straight line on said horizontal table, means for adjusting said second post about an axis eccentric to the axis 115 of the boring spindle, and means for rotating said boring spindles from said driving shaft.

5. In a multiple boring machine, a horizontal table, a vertical post rigidly mounted 125 on said table, a boring spindle supported by said post, a driving shaft parallel with said boring spindle, means for rotating said

shaft, a second boring spindle parallel with said driving shaft, means for adjusting said second boring spindle in a straight line on the plane of said horizontal table, independent means for adjusting said second boring spindle about an axis eccentric to the axis of the spindle, a belt connection between said sec-

ond boring spindle and said driving shaft, and automatic means for tightening said belt.
